UNITED STATES PATENT OFFICE.

JOSEPH SCHOENFELD, OF ALAMEDA, CALIFORNIA, ASSIGNOR TO THE MAGNAVOX COMPANY, OF SAN FRANCISCO, CALIFORNIA, A CORPORATION OF ARIZONA.

DESIGN FOR AN ELECTRIC-HEATER CASING.

Application filed February 18, 1925. Serial No. 12,415. Term of patent 14 years.

To all whom it may concern:

Be it known that I, JOSEPH SCHOENFELD, a citizen of the United States, residing at Alameda, in the county of Alameda and State of California, have invented a new, original, and ornamental Design for Electric-Heater Casing, of which the following is a specification, reference being had to the accompanying drawing, forming part thereof.

The figure is a perspective view of the electric heater casing.

I claim:

The ornamental design for an electric heater casing, as shown.

JOSEPH SCHOENFELD.
